Vacher, Santa Barbara, Calif.

Application October 19, 1931, Serial No. 569,710

7 Claims. (Cl. 299—67)

This invention relates to sprinklers, and particularly to a sprinkler of the rotary type of the character adapted to sequentially jet or project a stream of liquid, such as water, in a selected path of movement.

An object of the invention is to provide a sprinkler having a selected movement, whereby a given area may be continuously swept with a stream of liquid. In accomplishing the aforesaid object, we may, in one embodiment of our invention, provide two diametrically opposed nozzles, and so arrange the mechanism of the sprinkler that liquid is directed from one of said nozzles during a given arc of rotation, whereupon further flow of liquid through said nozzle is stopped and the flow of liquid directed through the other nozzle. Such a type of sprinkler is particularly useful for the wetting of selected areas of ground, such as on golf courses, and the like.

Another object is the provision of a sprinkler so arranged that the liability to damage is effectively obviated through provision of various and sundry safety devices incorporated within the sprinkler.

Another object is the provision of a sprinkler which is simple of construction, efficient in operation, fool-proof, of few parts, and generally superior to sprinklers adapted to accomplish a like function.

With the above and other objects in view, the invention consists in the novel and useful provision, formation, construction, association, and relative arrangement of parts, members and features, all as shown in a certain embodiment in the accompanying drawing, described generally, and more particularly pointed out in the claims.

In the drawing:

Figure 1 is a vertical sectional view of the improved sprinkler shown as an entirety,

Figure 2 is a sectional view on the line 2—2 of Figure 1,

Figure 3 is a sectional view on the line 3—3 of Figure 1,

Figure 4 is an enlarged fragmentary detail, partly in section, of certain locking mechanism used in practicing the invention, and,

Figure 5 is a fragmentary plan view of an element of the invention.

Referring to the drawing, the said sprinkler incorporates in its simplest embodiment a casing 1 formed in two parts, as shown at 2 and 3, which parts are adapted to be screw-threaded together as shown at 4. In the present instance, the casing is substantially circular in form. It will

be noted that the two-part casing has a chamber 5, the chamber being formed by the part 2 of the said casing having a side wall 6, a base 7, and an annular flange 8 extending outwardly from the base and centrally thereof. The part 3 of the casing has a side wall 9 and a top wall 10. Thus, when the two side walls 2 and 9 are threaded together, as shown at 4, the chamber 5 is formed. The top wall 10 has depending therefrom one or more valve guides 11. In the present instance, two valve guides are provided, as shown at 12 and 13. The top wall is enlarged, as shown in the drawing, and provided with one or more bores 14, each bore communicating with a valve guide 11. In the present instance, there would be two of said bores. The top wall is likewise bored, as shown at 15 and 16, said bores communicating with the bores 14, and nozzle members 17 are adapted for screw-threaded engagement with the walls bounding said bores 15 and 16. As shown, these said nozzles extend outwardly from the top wall at an angle to the longitudinal axis of the sprinkler. This so-called top wall has a chamber portion 18 formed by providing an annular wall 19 at what may be termed a sprinkler head. This wall is internally screw-threaded at 20 and adapted to have screw-threaded thereto a cap 21. As shown in Figure 2, said top wall is provided with a pair of oppositely disposed segmental ports 22 and 23 and these said ports communicate between the chambers 5 and 18.

Adapted for movement within the valve guides 11, and likewise within the bores 14 communicating with said guides, are poppet valves 24. In the present instance, two poppet valves are provided. Both poppet valves include a stem 25 having a fairly close fit engagement with the bore of the guides 11, with said stem enlarged at 26, finally terminating in a conical-shaped valve head 27. This valve head may be non-detachable from the stem although in the present instance, it is held to the stem through the medium of a screw or the like 28. The bore 14 has a larger diameter than the enlarged portion 26 of the stem, and said bore is likewise of considerably greater diameter than the diameter of the portion 25 of the stem. One end portion of this enlargement is annularly beveled, as shown at 29, and the wall bounding the bore 14 and the bore of the guide 11 is correspondingly beveled, as shown at 30, to receive the beveled portion 29, although in the present instance the two parts are not adapted to seat (see the closed valve of Figure 1). However, the top wall where it communicates with the chamber 18 is provided with

a beveled seat at 31 for receiving the valve head 27.

Within the chamber 5 is what may be termed a jetting head 32, the same including a member 5 having a base 33, an annular side wall 34, and a central annular flange 35 depending from the base. This annular flange is adapted to fit within the confines of the flange 8 and likewise extend beyond the end of the flange 8. It will 10 be seen from the drawing that the said jetting head is fairly closely confined within the part 2 of the casing 1. Between the bases 7 and 33 is a bearing washer 36, it being the intention that the casing should revolve relative to the jetting 15 head. The jetting head has spanning the annular side wall 34, a plate 37. This said plate is provided with one or more passages 38. These said jets are formed by upsetting the metal in the manner shown at 39, so as to have a depending portion extending relative to a surface of the plate, with a port 40 formed between the depending portion and the plate. The ports in each instance are so arranged that the same communicate with the space included between the 20 base 33 and the said plate, said ports in turn communicating with the opposite surface of the plate. Centrally mounted upon said plate and on what may be termed the exterior surface of the jetting head, is a cam 41. This cam is in the 25 form of a segmental helix. As shown, the said cam is held to the plate by any suitable means, such as by the screw shown at 42. The cam is so positioned relative to the valve stems, of which there are two in the present instance, that one 30 stem engages the cam at the lowest portion thereof at the time that the opposite stem is entirely raised. As shown in Figure 3, there is a sudden drop in the cam so that a valve will drop suddenly to close to its seat when the other valve 35 commences to open.

As stated, the casing is adapted to rotate relative to the jetting head, and it is essential that the valve stems be protected against damage during casing rotation. Hence, to prevent the 40 abrupt surface of the cam from breaking the stems if the casing was moved in a direction opposite to its normal direction of rotation, we have provided a spring catch. This spring catch includes a stem 43 having a head portion 44 and 45 around which stem and bearing against the head is a coil spring 45. The coil spring, stem and head are adapted to be in part confined within a bore 46 in the cam 41, see Figure 4. We also upset the metal of the plate 37 in the path of said head 50 44 by striking a portion of it downwardly, as shown at 47, so as to have an abrupt contact surface 48 and an inclined portion 49, against which surface 48 the head of the stem contacts when the casing is moved in its direction of normal 55 rotation.

Adapted to be loosely carried upon the top of the plate 37 is an annular ring 50. This annular ring is adapted to move against the inner surface of the side wall 9 in a manner to be set forth in the statement of operation. It is also to be noted that the inner surface of the wall 9 is provided with a pair of diametrically disposed segmental indentations 51 and 52.

The annular flange 35 is screw-threaded at 53 70 and a coupling 54 is secured to said screw-threads, and which coupling in turn directly connects with a pipe 55 leading to a source of liquid supply.

The operation, uses and advantages of the 75 invention just described are as follows:

Liquid under pressure is adapted to be delivered through the pipe 55 within the confines of the annular flange 35 and against the plate 37. This liquid in turn will pass through the ports 40 and be received within the confines of the annulus 50. The passages 38 are so formed as to direct the fluid against the inner wall of the annulus 50 and in so doing, the annulus is impelled to rotate. The annulus has its outer wall surface engaging the inner surface of the wall 9 10 and this annulus will, therefore, rotate against this surface and in so doing, rotate the casing. It is apparent that the bearing surface for the casing occurs between the annular flange 35 and the flange 8. As the casing rotates, the 15 valves are sequentially raised and lowered. Liquid being directed within the chamber 5 of the casing in turn flows through the ports 22 and 23, and is received in the space included between the valve heads and the cap 21. From 20 here, the liquid flows past the valve head and into the bore 26, thence into the nozzle 17. Within each nozzle is a deflector 56. In the present instance, the deflector is a flat plate diametrically spanning the nozzle for the purpose of directing 25 the liquid straight outwardly from the nozzle without giving the liquid a spiral movement. Intermittent rotation will occur between the casing 1 and the annulus 50 when the annulus 50 is received within one of the indented portions 30 51 or 52 of the wall 9. The casing will be rotated and when the annulus escapes from an indentation, no appreciable rotation of the casing will occur.

In actual use, the said sprinkler may be placed 35 in a given location relative to an area to receive liquid, and it is apparent that first one nozzle will direct a stream of liquid over a given arc, whereupon flow of liquid through said nozzle will cease, immediately followed by liquid being 40 directed through the other nozzle to cover the same arc of movement. Thus, it is possible to practically continuously direct a stream of liquid over the same area. By varying the number of nozzles as well as the arrangement of the cam, 45 it is possible to direct liquid over any arc desired.

The arrangement of the stop between the cam and the plate 37 is such that when the casing is revolved in a proper direction, the head 44 of the stem 43 engages the stop portion 48 of the 50 plate so that the cam is held against rotation during movement of the casing. It is, of course, understood that the top portion of the casing is revolved, which top portion has the valves mounted therein. When reverse direction of the 55 casing is attempted, the cam is released, the head 44 sliding upon the gradually curved portion 49, with the result that a stem of a poppet valve engaging the abrupt end wall of the cam, simply rotates the cam relative to the plate and 60 the screw 42.

The annulus 50 is of a sufficient diameter to at all times form an enclosure for that portion of the plate having the jets, and said annulus is always eccentric to the casing during operation 65 of the sprinkler.

The poppet valves may be of the gravity actuated type due to the fact that liquid under pressure is directed against the heads thereof. The valves are, therefore, raised through the 70 simple expedient of the cam to permit liquid to flow past the heads and stems into the nozzles.

It is obvious that various changes and modifications and variations may be made in practicing the invention in departure from the par- 75

ticular showing of the drawing without departing from the true spirit of the invention.

We claim:

1. In a sprinkler of the character disclosed comprising a water conveying and jetting device, a casing, means within said casing and acted upon by the water jetting device to rotate said casing, a sprinkler nozzle carried by the casing, a cam, and a poppet valve operated by said cam to alternately open and close communication between the casing and said nozzle during a given rotation of said casing. 5
2. A sprinkler of the character disclosed comprising a casing formed with opposed outlets, sprinkler nozzles fitted in said outlets, a liquid jetting device within said casing and arranged to be in communication with a source of liquid supply, means within the casing adapted to be acted upon by liquid jetted through said liquid jetting device to rotate said casing relative thereto, a cam, and poppet valves engaging the cam for alternately opening and closing the outlets through said casing during rotation thereof. 10
3. A sprinkler comprising a casing, a pair of poppet valves to control passage of liquid through the casing and outwardly thereof, said casing being constructed to be rotated, means arranged to alternately open and close a poppet valve during rotation of said casing in one direction, and means whereby the first named means is non-rotatable in the direction of normal rotation of said casing. 15
4. A sprinkler comprising a casing, a jetting head within said casing, said casing being adapted to revolve relative to the said jetting head, said jetting head including a plate formed with passages, means whereby a liquid may be passed within said jetting head and outwardly through said passages into the interior of the casing to produce rotation of said casing, a nozzle secured to the casing, a poppet valve mounted in a valve receiving port in communication with said nozzle and the interior of the casing, and means whereby said poppet valve is opened and closed during rotation of the said casing to control passage of liquid through the casing and outwardly of the nozzle during rotation of the casing a selected degree of revolution. 20
5. A sprinkler comprising a rotatable casing having two separated chamber portions and a port therebetween, a gravity actuated poppet valve formed to extend between said chamber portions in the casing, cam means for positioning the poppet valve during rotation of the casing, a nozzle secured to the said casing, said casing being adapted to receive a liquid in one chamber to be transmitted through said port to the other chamber, and said poppet valve when in one position permitting said liquid to pass through said last chamber into said nozzle and in a second position to close the passage between said last chamber and said nozzle. 25
6. A sprinkler comprising a casing having two separated chamber portions and a port therebetween, a poppet valve formed to extend between said chamber portions in the casing, cam means for positioning the poppet valve during rotation of the casing, a nozzle secured to the said casing, 30 said casing being adapted to receive a liquid in one chamber to be transmitted through said port to the other chamber, and said poppet valve when in one position permitting said liquid to pass through said last chamber into said nozzle and in a second position to close the passage between said last chamber and said nozzle, in combination with means in one of said chambers adapted to produce rotation of said casing when liquid is received therein. 35
7. A sprinkler comprising a casing having two separated chamber portions and a port therebetween, a poppet valve formed to extend between said chamber portions in the casing, a nozzle secured to the said casing, said casing being arranged to receive a liquid in one chamber to be transmitted through said port to the other chamber, said poppet valve when in one position permitting said liquid to pass through said last chamber into said nozzle and in a second position to close communication between said last chamber and said nozzle, in combination with means in one of said chambers adapted to produce rotation of said casing when liquid is received therein, and cam means to open and close said poppet valve during rotation of said casing. 40 45
